UNITED STATES PATENT OFFICE.

NATHANIEL L. BRADLEY, OF WEST MERIDEN, CONNECTICUT, ASSIGNOR TO
BRADLEY & HUBBARD, OF SAME PLACE.

DESIGN FOR LAMP-PEDESTAL.

Specification forming part of Design No. **7,161**, dated February 10, 1874; application filed January 15, 1874.
[Term of Patent 7 years.]

E.

To all whom it may concern:

Be it known that I, NATHANIEL L. BRADLEY, of West Meriden, in the county of New Haven and State of Connecticut, have invented a new Design for Lamp-Pedestal; and I do hereby declare the following, when taken in connection with the accompanying drawing and the letters of reference marked thereon, to be a full, clear, and exact description of the same, and which said drawing constitutes part of this specification, and represents a front view.

This invention relates to a design for a lamp-pedestal—that is, the support for the fount or burner; and the design consists in a female figure, in the position as hereinafter described, supporting a staff, upon which the fount or burner rests.

Upon a base stands a female figure slightly

stooping, one hand supporting a staff, upon which rests the lamp fount or burner, the other hand raised as if shading the eyes, as fully shown in the accompanying illustration.

The form of the base, fount, or burner is no part of the design, it being only essential that these parts in some form be present.

I claim as my invention—

The design for lamp-pedestal, consisting of the female figure standing upon a base, in one hand supporting a staff, upon which the lamp or burner rests, the head inclined forward, and the other hand raised, shading the eyes, as herein described, and shown in the accompanying illustration.

N. L. BRADLEY.
